[57] CLAIM

The ornamental design for a clamp for holding a towel
or the like on a bar, as shown.

DESCRIPTION

FIG. 1 is a perspective view of a clamp for holding a
towel or the like on a bar, showing my new design;
FIG. 2 is a side elevational view taken from the side
opposite that shown in FIG. 1;

FIG. 3 is a bottom plan view thereof;

FIG. 4 is an end elevational view taken from the right of
FIG. 1.

FIG. 1

FIG. 2

FIG. 3

FIG. 4
